UNITED STATES PATENT OFFICE.

ELIZABETH CALKINS, OF ST. JOSEPH, MISSOURI.

VEST.

1,236,279.

Specification of Letters Patent.

Patented Apr. 6, 1920.

Application filed August 8, 1919. Serial No. 316,208.

To all whom it may concern:

Be it known that I, ELIZABETH CALKINS, a citizen of the United States, and a resident of St. Joseph, in the county of Buchanan 5 and State of Missouri, have invented a new and Improved Vest, of which the following is a full, clear, and exact description.

This invention relates to a vest, and aims to provide a device of this nature whereby 10 the shoulder straps provided with a conventional shirt or vest may be eliminated.

It is a well-known fact, particularly in connection with evening dress, that great difficulty is experienced in preventing the 15 shoulder straps of a lady's shirt or vest from becoming visible, and for this reason they are usually tucked inside one of the nether garments. During subsequent movement of the body, such as in dancing, this 20 arrangement often results in the straps becoming cumbersome, and there is also the danger of their working out to the embarrassment of the wearer.

For this reason I have devised a vest or 25 shirt which may be worn in connection with the corset, so that the same is supported by the corset, thus eliminating the necessity for shoulder straps. While this arrangement is particularly to be desired in connection with 30 evening dress, I wish to point out that the same might readily be utilized in every-day wear.

It will further be seen, particularly where the vest is provided with small sleeves, that 35 tucking such sleeves inside the corset would cause the wearer to become extremely warm at these points.

A further object of the invention is the provision of means associated with such vest 40 which will render the same capable of conforming to the corset and body when the laces, usually provided at the rear of the corset, are properly adjusted so that the corset is correctly applied.

Reference is had to the accompanying drawings which illustrate one practical embodiment of my invention, and in which:—

Figure 1 is a front elevational view of a closed corset with my vest or shirt attached 50 thereto; and

Fig. 2 is also a front elevational view with the corset open and one corner of the vest or shirt detached therefrom so as to disclose the method of application.

55 In these views like reference characters designate corresponding parts in all the

views and the reference character 1 indicates the conventional corset provided with the usual laces 2. A shirt or vest 3 is secured to the inner face of the corset by 60 means of snap fasteners 4.

This vest is provided with a draw string 5. To provide a vest which will accommodate itself to all adjustments of the corset, I find it necessary to make the same with a 65 certain fullness at a point underlying the strings of the corset, as indicated by the reference numeral 6. It is also advantageous to have the vest, as indicated by the reference numeral 7, cut so as to provide a 70 certain fullness at points overlying the upper sides of the body.

The vest may be of any length or provided with any fancy-work desired. The vest is entirely removable from the corset, 75 by means of the snap fasteners 4, for the purpose of washing. It will be understood that the reason for cutting such vest or shirt slightly fuller than is the common practice is that corsets when new are inclined to 80 stretch and shape themselves to the contour of the body. During this period it is necessary to secure a proper adjustment, so that the corset may not be uncomfortable, by means of the draw string 2, and it will be 85 seen that the fullness mentioned is essential to permitting this adjustment.

From the above it will be seen that I have constructed a sleeveless vest which may be applied to any corset and which can, obviously be made of any suitable material. 90 It will further be seen that by having the vest fit the lower edge of the corset loosely, with an extra fullness in the center of the back and a small amount of fullness toward 95 the front, with a corresponding fullness adjacent the upper parts of the corset, the wearer will be capable of drawing up the vest so as to adjust the abdomen, which is naturally depressed in applying any corset. 100

As aforesaid, when the corset is new the space in the back is much greater than when such corset has been worn long enough for the same to conform to the figure of the wearer. During this period of adjustment 105 the extra fullness in certain portions of the vest may be let out so as to conform to the corset. This adjustment is also very desirable after a corset has been washed, at which time the same must again pass 110 through this rearrangement.

It is to be further appreciated that any

number of modifications in structure may be employed without in the slightest departing from the scope of my claims, as, for instance, forming a special kind of plait to accommodate the fullness of the vest or shirt, substituting different forms of fastening means in lieu of snap fasteners, etc.

Having thus described my invention, I desire to claim:

- 10 1. An article of apparel including, in combination with a corset, a shirt attached to the inner face thereof.
2. An article of apparel including, in com-

bination with a corset, a shirt removably attached to the inner face thereof.

3. An article of apparel including, in combination with a corset, a shirt attached to the inner face thereof, such shirt being cut full at a point underlying the conventional draw strings of the corset.

4. An article of apparel including, in combination with a corset, a shirt attached to the inner face thereof, said shirt being cut so as to provide a slight fullness at the upper ends of the sides of the corset.

MRS. ELIZABETH CALKINS.
